HOLDER FOR A PAIR OF SPECTACLES

Vernon L. Wantz, Minneapolis, Minn.

Application January 11, 1954, Serial No. 28,445

Term of patent 14 years

(Cl. D57—1)

To all whom it may concern:

Be it known that I, Vernon L. Wantz, a citizen of the United States of America, residing at Minneapolis, county of Hennepin, Minnesota, have invented a new, original, and ornamental Design for a Holder for a Pair of Spectacles, of which the following is a specification, reference being made to the accompanying drawing, forming a part thereof, and in which:

Fig. 1 is a front perspective view of a holder for a pair of spectacles embodying my new design;

Fig. 2 is a top plan view thereof; and

Fig. 3 is a front elevational view thereof.

I claim:

The ornamental design for a holder for a pair of spectacles, substantially as shown.
